UNDERFIRED COKE OVEN

Carl Otto, New York, N. Y., and Frans Wethly,
Manhasset, N. Y., assignors to Fuel Refining
Corporation, Dover, Del.

Application November 28, 1940, Serial No. 367,506

8 Claims. (Cl. 202—151)

The general object of the present invention is to provide improved means for supplying "rich" fuel gas to the combustion flues of an underfired coke oven battery. The term "rich fuel gas," as used herein, means a gas which, like ordinary coke oven gas, has a B. t. u. value higher than ordinary producer or blast furnace gas, and which is not regeneratively preheated before its passage into the coke oven combustion flues in which it is burned.

Heretofore it has been customary to supply rich fuel gas to the combustion flues of underfired coke oven batteries through horizontal distribution pipes located in the basement space beneath the masonry including the coke oven brickwork and its supporting deck of reinforced concrete. Such distribution pipes extend transversely of the battery, and each supplies gas to a plurality of vertical heating flues in a single heating wall through corresponding branch pipes, each of which includes a regulating device accessible for adjustment from the basement space.

When gas is supplied through the distribution pipes located in the basement space of the battery, as described, there is a possibility that the gas passing through the pipe will occasionally be cooled to a temperature low enough to effect the condensation of water, naphthalene, and other vapor constituents. The presence of water of condensation in the distribution pipes is objectionable, especially if the gas contains H₂S as is frequently the case, since the water and H₂S initiate chemical reactions, resulting in the deposit of sulphur, which may eventually clog up the distribution pipes and their branch outlets. Clogging difficulties result also from solid deposits of condensed naphthalene and in some cases, the condensation occurring in the pipes may result in their corrosion.

To avoid objectionable condensation in distribution pipes located in the basement space of underfired coke ovens, the gas is sometimes preheated prior to its introduction into the distribution pipes, but such preheating requires additional apparatus and involves expense. All risk of such condensation may be avoided by locating the distribution pipes in the reinforced concrete deck which forms the basement space roof and supports the coke oven brickwork in the manner as disclosed in the van Ackeren Patent 2,205,839, granted August 2, 1939. When the distribution pipes are so incorporated in the deck, the heat transmitted by the coke oven brickwork to the deck heats the distribution

pipes to temperatures high enough to preclude condensation in the pipes.

Some objection to the incorporation of the rich fuel gas distribution pipes in the concrete supporting deck of an underfired coke oven battery has been suggested on the ground that with such an arrangement, defects may develop in the piping embedded in the masonry which may be difficult or practically impossible to correct or eliminate. While we think that such objections have little or no practical justification, the specific object of the present invention is to devise an arrangement in which the rich fuel gas distribution pipes are so located beneath the concrete deck, so as to be accessible for repairs and replacement, but are so disposed and have their branch outlets so disposed as to absorb sufficient heat from the deck to eliminate the risk of objectionable condensation in the distribution pipes and their branches.

The various features of novelty which characterize the invention are pointed out with particularity in the claims annexed to and forming a part of this specification. For a better understanding of the invention, however, its advantages, and specific objects attained with its use, reference should be had to the accompanying drawings and descriptive matter in which we have illustrated and described preferred embodiments of the invention.

Of the drawings:

Fig. 1 is a partial transverse section of a coke oven battery, taken on the line 1—1 of Fig. 2;

Fig. 2 is a partial longitudinal section of the battery taken on the broken line 2—2 of Fig. 1;

Fig. 3 is an enlarged reproduction of a portion of Fig. 2;

Figs. 4, 5, 6, 7 and 8 are views each taken similarly to Fig. 3, and each illustrating a different modification of the construction shown in Fig. 3.

In Figs. 1-3, we have illustrated the use of the present invention in a horizontal underfired regenerative coke oven battery comprising a concrete layer or deck A, which directly supports the coke oven brickwork, and forms the roof of the basement space a of the battery. The deck A is supported by beams C, which, in the construction shown in Figs. 1-3, extend transversely of the battery and are carried by columns or posts CA extending upwardly through the basement space a from the usual battery foundation or mat (not shown).

The coke oven brickwork B comprises a lower story or section, and an upper story or section.

In the lower section, regenerator division walls D and d alternate along the length of the battery, each extending from one side of the battery to the other, and between each adjacent pair of walls D and d, is a regenerator E or e extending from one side of the battery to the other. As shown, the different regenerators E and e are similar in construction, but the regenerators E are used in preheating combustion air only, while the regenerators e are used to preheat either lean fuel gas or air, accordingly as the oven is heated by the combustion of lean gas which requires preheating, or by the combustion of rich gas which does not require preheating. Pairs of regenerators E alternate with pairs of regenerators e along the length of the battery.

The upper story or section of the coke oven brickwork mass B is shown as of well known type comprising horizontally elongated coking chamber F, alternating with heating walls G, each of the chambers and walls extending from one side of the battery to the other. Each heating wall G is formed with vertical flues g and g' alternating with one another in a row extending from one side of the battery to the other. Each flue g and an adjacent flue g' are connected at their upper ends and collectively form a so-called hairpin flue. Each heating wall G is directly above a corresponding regenerator division wall D, which may therefore be aptly called a pillar wall, and beneath each coking chamber F is an intermediate regenerator division wall d.

Beneath each of the regenerators E and e is a corresponding sole channel E' or e', respectively, through which the waste heating gases which flow down through the regenerator, when the latter is serving as an "off" regenerator, pass to one or both sides of the battery, and thence through the usual reversing valves to the waste heat flue system which forms no part of the present invention and may be of the usual type, and hence need not be illustrated or further described. Each of the regenerators E and e is connected at its upper edge by channels E² or e² in the brickwork to the lower end of one limb, g or g', of each of the hairpin flues in each of the two heating walls G directly above the two immediately adjacent pillar walls D between which the regenerator is located, and each hairpin flue limb is connected by a channel E² to the regenerator E at one side of the subjacent pillar wall D, and is connected to the regenerator e at the other side of said pillar wall by a second channel e². The combustible agent, air or lean gas, pre-heated in each of the regenerators E and e, may be supplied to the regenerator in which it is pre-heated through the corresponding sole channel E or e, or, as shown, through a corresponding distribution pipe H or h, each of said pipes being embedded in the concrete layer A, and being formed with a multiplicity of outlets distributed along the length of its top wall. The flow through each of said outlets may be regulated by the size of the measuring orifice or nozzle passage in a nozzle member H' threaded into or otherwise replaceably mounted in the outlet opening. Each nozzle H' discharges into a corresponding uprising passage A' formed in the layer A and communicating at its upper end with the lower end of a corresponding brickwork channel E³ or e³ formed in the adjacent pillar wall D and connected at its upper end, to the corresponding regenerator E or e.

In heating the battery by the combustion of rich fuel gas, the latter is supplied to the vertical

flues g and g' through channels J and JA leading upward through the deck A and intermediate regenerator division walls d. As shown, there are a set of channels J and a set of channels JA in each wall d. The channels J in each wall d correspond in number to and are connected to one set of hairpin flue limbs g or g' in one adjacent heating wall, and alternate along the length of the wall with the channels JA in that wall, said channels JA being connected to the hairpin flue limbs g or g' in the other heating wall adjacent the wall D. The various hairpin flues in each heating wall thus have the lower ends of their limb g connected to uprising channels J or JA in the adjacent regenerator division wall d at one side of the heating wall, and have their limbs g' connected to uprising channels J or JA in the adjacent regenerator division wall d at the opposite side of the heating wall. The lower portions of the channels J and JA are vertical and centrally disposed in the corresponding division wall d, but the upper portions of the channels J curve away from that wall toward the other of the two adjacent heating walls.

In the form of the invention shown in Figs. 1-3, each of the channels J and JA has its lower portion lined by a tubular metallic part JB incorporated in the lower portion of the deck layer A, and having a lateral gas inlet within the deck layer and having its lower end extending downward into the basement space and normally closed by a cap or plug member JB', which can be removed to permit the channel to be inspected or cleaned, or temporarily filled by liquid cement to close leaky walls, joints, or cracks. Each of the channels J and JA in a single regenerator division wall d may simultaneously receive rich fuel gas through its lateral gas inlet and an individual branch from a horizontal distribution pipe HA located in the upper portion of the basement space a, adjacent, but slightly to one side of the corresponding row of caps JB'.

As shown, each of said distribution pipe branches comprises a vertical nipple h' having its upper end screwed into the vertical lower end of an elbow h² and having its enlarged lower end screwed into a threaded outlet opening formed in the pipe HA at its upper side. The horizontal upper end of the elbow h² is connected by a horizontal nipple h³, to the metallic part JB in the corresponding channel J or JA. The nipple h³, elbow h² and the upper portion of the nipple h' are all located within the deck layer A. As shown, however, the nipple h' can be rotated to disconnect it from and reconnect it to the pipe HA and to the corresponding elbow h², by a suitable wrench or other implement extending into and across the pipe HA through an opening in the bottom wall of the pipe normally closed by a plug h⁴, and large enough to permit the passage of the nipple h'. The rate of fuel gas flow through each branch pipe connection, is regulated in the construction shown in Fig. 3, by the size of the orifice in an externally threaded orifice K screwed into an internally threaded seat portion of the nipple h'. Each orifice member K can be removed and replaced by another having an orifice of different flow capacity by a suitable tool extending across the pipe HA, and into engagement with the member K, through the bottom wall opening in the pipe HA normally closed by the corresponding plug h⁴.

As shown, the lower half of the pipe HA is within a trough-shaped body Q of heat insulat-

ing material supported from the pipe, the sides of the body Q being spaced away from the adjacent portions of the pipe HA to provide a heat insulating dead air space. With the pipe HA supported within a few inches of the underside of the deck and with the member Q minimizing the heat losses from the underside of the pipe, the latter will be maintained at a temperature high enough to preclude condensation therein even under extreme climatic conditions. Moreover, as is clearly shown in Fig. 3, each orifice member K is within the deck A, so that under all conditions it will be maintained at a temperature appreciably higher than the temperature of the pipe. The resultant additional security against condensation in the orifice members is desirable because of the small orifice diameters of such members, and the fact that only a very slight clogging of an orifice by condensed material may objectionably reduce the fuel supplied through that orifice effect the fuel distribution.

The arrangement shown permits the pipe HA to be located adjacent the ceiling of the basement space so that it offers little interference to movements of attendants through said space while at the same time the pipe is readily accessible for repairs or replacement.

The general advantages of the present invention can be obtained with different constructions and arrangements, some of which are shown in Figs. 4-8 inclusive.

In the modification illustrated in Fig. 4, the branch pipe connection between each tubular metallic part JB and the corresponding pipe H comprises a bent pipe h^5 having a lower vertical portion connected by a union h^6 to a tubular outlet branch h^7 of the pipe HA. The horizontal upper end portion of the pipe h^5 is connected to the nipple h^3 and thereby to the corresponding metallic part JB, through a vertically disposed tubular member L. The latter is incorporated in the deck layer A, and is provided with an internally threaded seat for a removable orifice member K, which when screwed in said seat, is located above the level of the pipe h^5 , and below the level of the nipple h^3 . The orifice member K of Fig. 4 is accessible for cleaning and replacement through the lower end of the member L, on the removal of the plug L' normally closing said end. As shown, the plug L' is formed with a recess or seat L^2 for the lower end of a wire or rod M, which may extend upward through the orifice in the member K, to reduce the flow capacity of the latter by a small amount. Greater changes in the orifice flow capacity may be effected by replacement of the orifice member K in use, by one of different flow capacity.

The modified form of our invention shown in Fig. 5 differs from that shown in Fig. 4 by the replacement of the member L incorporated in the layer A by the body or casing N of a reversing cock or valve. As shown, the body N is formed with a vertical tapered valve chamber N' and horizontal ports N^2 and N^3 at its opposite sides, respectively communicating with the bent pipe h^5 and with the nipple h^3 . A frusto-conical plug valve n, fitting in the valve chamber N', is formed with a horizontal through passage n' , receiving a replaceable orifice member n^2 , and is adapted to establish or cut off communication between the ports N^2 and N^3 , accordingly as the plug valve is turned into one or another angular position in the chamber N'. The valve n has a stem n^3 extending axially downward from its

lower end. A horizontal operating lever n^4 is secured to the stem n^3 , which may be connected to the usual automatic reversing mechanism employed to periodically reverse the direction of gas flow through the flues and reegegenerators of a regenerative coke oven. As shown, the valve n is removably secured in place in the valve body N by a clamping member or a head N^4 connected to the valve body by stud bolts N^5 , and engaging the lower end of the valve.

As shown, decarbonizing air may be supplied to the tubular member JB of Fig. 5, through the corresponding valve n when the latter is turned into the angular position in which it closes communication between the ports N^2 and N^3 . In that position, an air passage n^6 extending axially through the valve stem portion n^3 has its laterally extending upper end in register with the port N^3 . When the valve n is turned to bring the ends of its passage n' into register with ports N^2 and N^3 , the upper end of the passage n^6 is closed by the conical wall of the valve chamber N'. The lower end of the air passage n^6 is open to the atmosphere at all times.

In the normal operation of an ordinary under-fired coke oven battery, it is desirable and customary to pass decarbonizing air into the vertical oven fuel gas channels, such as the channels J and JA, during approximately one half the time, i. e., during each of the regenerator reversal periods in which fuel gas is not being supplied to said channels. With the arrangement shown in Fig. 5, the decarbonizing air supplied to the channels J and JA does not pass through the distribution pipe HA from which the channels are supplied with rich fuel gas during alternate reversal periods. The arrangement shown in Fig. 5 thus avoids the risk of the objectionable sulphur deposits in the distribution pipes which exist when those pipes are used to alternately supply fuel gas and decarbonizing air to the vertical channels. This is due to the fact that ordinarily, the chemical reactions which result in the deposit of sulphur in the distribution pipes, require the presence, although not necessarily the simultaneous presence, in the distribution pipe, of oxygen, water and a gas having a sulphur content.

In the form of our invention shown in Fig. 6, each channel J, and JA, receives rich fuel gas through a pipe O extending vertically through the deck layer A and connected at its lower end to a T, or cross shaped fitting P, having one channel branch connected by a horizontal nipple h^{10} to the corresponding distribution pipe HA, and having an aligned horizontal opening closed by a plug H'' which can be removed to permit replacement of the orifice member KA, which is screwed into the horizontal branch to which the nipple h^{10} is connected. A plug P' normally closes the end of the fitting P beneath and in register with the pipe O, but may be removed to open the channel J for inspection or cleaning and repair purposes.

To permit the deck layer A and superposed portion of the battery structure to be supported by beams R running longitudinally of the battery, as disclosed and claimed in the prior patent application, Serial No. 314,760, filed January 20, 1940, by Carl Otto, one of the applicants herein, the pipe HA shown in Fig. 6 is located within a recess A^{10} formed in the underside of the deck layer A, beneath the corresponding regenerator division wall d. To increase the temperature to which the pipe HA and orifice members KA are

heated by the deck layer A, heat insulating walls QA may be provided beneath the recesses A¹⁰. As shown, each wall QA is normally supported in a horizontal position by a hinge connection Q' to the layer A at one side of the wall, and by a pivoted detent Q² releasably connecting the opposite side of the wall to the deck layer A.

In the form of our invention shown in Fig. 7, the distribution pipes HA which supply rich fuel gas to the uprising channels in the regenerator division walls d, are above the longitudinal deck supporting beams R, each pipe HA being received in a recess in deck layer A, as in the construction shown in Fig. 6. In the Fig. 7 arrangement, however, the insulating walls Q are omitted and the branch pipe connections from the pipes HA are like those shown in Fig. 3, each including an orifice member K located in the portion of the nipple h' which is within the deck layer A and receives heat directly therefrom by conduction.

When the battery is supported by longitudinal beams R, as shown in Figs. 6, 7, and 8, the reinforcing effect on the deck concrete layer A of the transversely extending distribution pipes H and h incorporated in said layer, may be supplemented, when necessary, by the effect of other reinforcing means incorporated in the layer A, such, for example, as the I-beams S shown in Figs. 6, 7, and 8, and which may extend from one side of the battery to the other.

If, for any reason, it is undesirable to locate the distribution pipes HA above the deck supporting beams R extending longitudinally of the battery, as they are located in the constructions shown in Figs. 6 and 7, the distribution pipes may be located beneath the beams Q, or each of those pipes may extend through corresponding openings formed in the central portion of each beam, as shown in Fig. 8.

While in accordance with the provisions of the statutes, we have illustrated and described the best form of embodiment of the invention now known to us, it will be apparent to those skilled in the art that changes may be made in the form of the apparatus disclosed without departing from the spirit of the invention as set forth in the appended claims and that in some cases certain features of the invention may be used to advantage without a corresponding use of other features.

Having now described our invention, what we claim as new and desire to secure by Letters Patent, is:

1. An underfired regenerative coke oven battery comprising a mass of masonry above a basement space, regenerator division walls in the lower portion of said mass, oven heating walls lo-

cated in the upper portion of said mass and formed with combustion flues, uprising rich fuel gas supply channels formed in said division walls and connected at their upper ends to said flues, rich fuel gas distribution pipes beneath said mass and conduit connections between each of said pipes and a plurality of said channels each of which comprises a restricted orifice portion which is in position to absorb heat from said mass and is surrounded by heat insulating material.

5 2. A coke oven battery as specified in claim 1, in which the restricted orifice portion of each of said connections is embedded in and insulated by said masonry mass.

3. A coke oven battery as specified in claim 1, in which each conduit connection includes a lower vertical portion and an upper horizontal portion both imbedded in said masonry mass and in which an orifice member is removably secured 15 in said vertical portion.

20 4. A coke oven battery as specified in claim 1, in which each conduit connection includes a portion which is embedded in said masonry mass and includes a restricted orifice and a reversing 15 valve.

25 5. A coke oven battery as specified in claim 1, in which each conduit connection includes a portion embedded in said masonry mass and including a restricted orifice and a reversing valve, 30 and in which said reversing valve is provided with a decarbonizing air inlet.

35 6. A coke oven as specified in claim 1, in which said masonry mass is supported on beams extending longitudinally of the battery and in which said mass is formed with recesses in its under side extending transversely of the battery and in which said distribution pipes are located above said beams and in said recesses.

40 7. A coke oven battery as specified in claim 1, in which said masonry mass is supported on beams extending longitudinally of the battery and in which said mass is formed with recesses in its under side extending transversely of the battery, and in which said distribution pipes are located above said beams and in said recesses, and in which heat insulating material is located beneath said distribution pipes.

45 8. A coke oven battery as specified in claim 1, in which each of the uprising rich fuel gas supply channels is provided at its lower end with a closure accessible for removal from beneath said masonry mass, and in which each of said conduit connections includes a portion embedded in said masonry and opening to the corresponding supply channel at a level above the closure therefor.

CARL OTTO.
